UNITED STATES PATENT OFFICE.

JAMES J. LAWLER, OF MOUNT VERNON, NEW YORK.

STEAM-VALVE.

No. 893,527.

Specification of Letters Patent.

Patented July 14, 1908.

Application filed May 6, 1907. Serial No. 371,999.

To all whom it may concern:

Be it known that I, JAMES J. LAWLER, a citizen of the United States, residing at Mount Vernon, Westchester county, New York State, have invented a new and useful Improvement in Steam-Valves, of which the following is a specification.

My invention relates to steam valves and has for its objects the production of a valve 10 having a controlling means for regulating the flow of steam and an independent noiseless and automatic means of permitting the return of the water of condensation to the source of supply, particularly when used on 15 a "one pipe" heating system, under a low pressure, or when used on a vacuum system of heating.

It is found, in ordinary practice, that a "one pipe" system of the kind mentioned 20 cannot be regulated to work satisfactorily on moderately warm days; the valve must be turned on sufficiently to not only permit the steam to enter the radiator to which it is attached, but also to permit the return of the 25 water of condensation, and when thus set, the entire radiator is filled with steam and is usually too hot on many days in spring and autumn, when only a little heat is desired. When opened only partly to get this desired 30 result, the radiator will be satisfactory only so long until the said water begins to return, when it meets the incoming steam which forces it back and causes the radiator to "hammer," to overcome which the valve 35 must be turned on full or closed off entirely. To overcome this difficulty in the valve shown in the accompanying drawing, in which

Figure 1 is a central vertical sectional view of my improved valve, the check valve being 40 closed. Fig. 2 is a sectional plan view on line X—X on Fig. 1, the check valve and plug being removed, and Fig. 3, is a radiator, partly in central section, having a valve of my improved construction connected, the 45 valve being also partly in section and in solid outline, the check valve being open.

Like reference characters denote corresponding parts throughout the several views.

Referring to the drawings, 1 denotes a 50 valve stem having the end walls of which threaded as at 3. The stem 1 extends through the hood 4 which is secured to the valve casing 10 and is provided with a stuffing box 5. The hood 4 is formed with 55 screw threads adapted to mesh with the screw threads 3 of the stem. Carried on that

end of the stem which is arranged within the valve casing 10 is a carrying member 7 having a valve disk 6, the latter being suitably connected to the frame. The valve casing is 60 formed with an interiorly screw-threaded inlet end 8 and an exteriorly screw-threaded outlet end 9. Arranged within the valve casing 10 is a vertically extending hollow tubular member 11, the top edge thereof constituting a seat for the valve disk 6 and the lower end thereof terminating in the inner face of the wall of the valve casing and formed in connection with the wall a pocket 70 12 which is permanently in communication with the outlet end of the valve casing and normally out of communication with the inlet of the valve casing. The tubular extension 11 is adapted to establish communication between the inlet and outlet of the casing. The valve casing 10 is provided with an extension 13 closed by a plug 14 to permit of the arranging within the valve casing of a check valve 15 which constitutes a means for normally closing the pocket 12 to the inlet 80 end of the valve casing. The check valve 15 is at an angle so that it will automatically close by gravity when pressure upon its inner face is removed. The check valve 15 is what may be termed a pressure operated valve 85 and the manner in which it is operated establishes communication between the pocket and the inlet valve casing will be hereinafter referred to.

The operation of the valve is as follows: If 90 the valve is attached to a radiator, as shown, in Fig. 3—and it is desired to turn on a little steam, as shown by position of disk in Fig. 1, the steam will enter the radiator, where it is condensed, the water returning back through 95 the radiator and into the pocket formed by the tubular member 11, the top edge of which forming an elevated valve seat for the valve disk 6, and when the weight of the water overcomes the weight of the check valve, 103 the latter will open and permit the water to flow through it, without distributing the flow of the incoming steam, thereby avoiding the hammering or gurgling which is incidental to the use of the valves heretofore.

At the same time my improved valve can be used under pressure the same as any ordinary radiator valve on a one pipe heating system, by opening the controlling valve to its full capacity, thus allowing the radiator 111 to fill with steam pressure carried on boiler, and under this condition my improved valve

is an improvement for the reason that the water of condensation travels to main flow pipes through the check valve passage which results in keeping the radiator more dry than 5 would be possible by using one valve of ordinary construction. This constitutes what I at present regard as the best known form of the invention but to the details of which my invention is not, in all respect, restricted, as 10 many changes in detail and many apparently widely different variations thereof may be made without departing from the spirit of the invention or the scope of the subjoined claims.

15 What I claim as new and desire to secure by Letters Patent is—

1. A steam valve comprising a casing having an inlet and an outlet, a vertically extending hollow tubular member arranged 20 within the casing and having its lower end terminating in the wall of the casing at a point removed from said inlet, a lower portion of said member in connection with the wall of the casing forming a pocket normally 25 out of communication with and above said inlet, and a pressure operated means for establishing communication between the pocket and the inlet, said member establishing communication between the inlet and the 30 chamber formed by the casing and the upper end of said member forming a valve seat, combined with a manually operated valve adapted to engage said seat.
2. A steam valve comprising a casing having 35 an inlet and an outlet, a hollow tubular member arranged within the casing and having one end terminating in the wall of the casing at a point removed from the inlet thereof, that portion of the member which terminates 40 in the wall of the casing forming in connection with the wall a pocket normally out of communication with the inlet, the free end of said member constituting a valve seat, said tubular member establishing communication 45 between the inlet and the chamber formed by the casing a manually shiftable valve

adapted to engage said seat, and an automatically operable pressure operated means for establishing communication between the pocket and the inlet, said means adapted 50 to return to closing position by gravity when pressure is removed therefrom.

3. A steam valve comprising a casing having an inlet and an outlet, a hollow tubular member having a fixed lower end, arranged 55 in said casing and forming in connection with the casing a pocket normally out of communication with the inlet, said member extending above said inlet and establishing communication between the inlet and the 60 chamber formed by the casing, a manually operated valve adapted to engage the free end of said member to close it, and a pressure operated means for establishing communication 65 between the pocket and the inlet.

4. A steam valve comprising a casing having an inlet and an outlet, an elongated hollow tubular member extending within said casing forming in connection with the valve 70 casing a pocket and further constituting an elevated valve seat, a manually operated valve adapted to engage said seat to close said member, said member establishing communication between the inlet and the casing formed by the chamber when the valve is removed from the seat, said pocket normally 75 out of communication with said inlet, and an automatically operable pressure operated means adapted when pressure is applied to one side thereof to establish communication 80 between said pocket and the inlet, said means adapted to automatically return to inoperative position by gravity.

In testimony whereof, I have signed my name to this specification in the presence of 85 two subscribing witnesses, this twenty-ninth day of April 1907.

JAMES J. LAWLER.
